(57) **CLAIM**

The ornamental design for a mobile data input keyboard, as shown and described.

DESCRIPTION

The design is a Data Input Board also known as Keyboard or Keypad which can be attached, permanently or detachable, primarily to Mobile Communicating Computers (MCC) such as PDAs, Cell-Phones, Smart-phones, Tablet PCs, Remote Controls, but also to PCs & Controls.

FIG. 1 is an isometric view of a mobile data input keyboard showing my new design;

FIG. 2 is an isometric view of a second embodiment thereof;

FIG. 3 is an isometric view of a third embodiment thereof;

FIG. 4 is an isometric view of a fourth embodiment thereof;

FIG. 5 is an isometric view of a fifth embodiment thereof; and,

FIG. 6 is an isometric view of a sixth embodiment thereof.
